CLAIM

The ornamental design for a notebook computer as shown and described.

DESCRIPTION

FIG. 1 is a front view of a notebook computer showing our new design;

FIG. 2 is a rear view thereof;

FIG. 3 is a left side view thereof;

FIG. 4 is a right side view thereof;

FIG. 5 is a top view thereof;

FIG. 6 is a bottom view thereof;

FIG. 7 is an enlarged view of the portion, labeled '7' of FIG. 1; and,

FIG. 8 is an enlarged view of the portion, labeled '8' of FIG. 1.

Dot-dash broken lines depict the boundary of the claim and form no part thereof. Dot-dot-dash broken lines define the extents of the enlarged views and form no part of the claimed design. All other broken lines depict portions of the notebook computer that form no part of the claimed design.
